UNITED STATES PATENT OFFICE

156,832

COMBINATION CLAW HAMMER AND SCREW DRIVER

Henry Jackson, New Comerstown, Ohio, assignor
to Heller Brothers Company, Newark, N. J., a
corporation of New Jersey

Application December 15, 1948, Serial No. 150,169

Term of patent 3½ years

(Cl. D93—4)

To all whom it may concern:

Be it known that I, Henry Jackson, a citizen of the United States, residing at New Comerstown, in the county of Tuscarawas and State of Ohio, have invented a new, original, and ornamental Design for a Combination Claw Hammer and Screw Driver, of which the following is a specification, reference being had to the accompanying drawings, forming a part thereof.

In the drawings:

Fig. 1 is a side elevational view of the combination claw hammer and screw driver, showing my new design; and

Fig. 2 is a top plan view of the same.

I claim:

The ornamental design for a combination claw hammer and screw driver, as shown.

HENRY JACKSON.
